UNITED STATES PATENT OFFICE

WALTER SCHOENI, OF BADEN, SWITZERLAND, ASSIGNOR TO AKTIENGESELLSCHAFT BROWN BOVERI & CIE, OF BADEN, SWITZERLAND, A JOINT STOCK COMPANY OF SWITZERLAND

SHIP-PROPULSION SYSTEM

Application filed August 8, 1928, Serial No. 298,214, and in Germany August 8, 1927.

It has already been proposed to utilize the exhaust steam of piston steam engines, intended more particularly for driving ships' propellers, in exhaust steam turbines and to utilize the power of these exhaust steam turbines for increasing the power or for increasing the efficiency of the propeller drive. The exhaust steam turbines as a rule work on to the same propeller shaft as the piston steam engines and drive the said shaft directly or through the intermediary of a transmission gear. It has also been proposed to introduce between the exhaust steam turbine and the propeller shaft driven by the piston engine, electric transmission gear consisting of a generator driven by the turbine and a motor fed by the latter and mounted on the propeller shaft.

The invention relates to an arrangement of the latter kind and consists in this, that the reversal of the direction of revolution of the piston engine and of the motor is effected simultaneously by the controlling gear of the former.

In the accompanying drawing a constructional example of a reversing arrangement according to the present invention is shown.

K is the piston steam engine which drives the propeller shaft P on which the motor M is mounted and T is the exhaust steam turbine which drives the generator G feeding the motor M. The hand-operated lever U for reversing the piston steam engine at the same time forms the controlling lever for the double pole electro-magnetically operated switches S₁, S₂, lying in the conductors connecting the generator and motor. The controlling lever is provided with brushes which bridge over sliding contacts of an auxiliary circuit for controlling the switches S₁, S₂. When the piston engine is reversed by reversing the lever U from ahead to astern, through the sliding contacts being bridged over, either the switch S₁ or the switch S₂ is connected to the auxiliary source of current. The particular switch becomes operative and alters the current between the generator and motor whereby the direction of rotation of the motor is changed. The switch S₁ may for instance

be used for going ahead and the switch S₂ for going astern. In this way the generator and the exhaust steam turbine maintain their direction of rotation, that is to say the exhaust steam turbine always runs in the same direction, irrespective of whether the piston steam engine is running forwards or backwards.

The reversal in the direction of rotation of the motor may be effected for instance in the case of alternating current motors, by reversing the rotating field and in the case of continuous current motors by reversing the current in the rotor circuit. For a slow running motor a three-phase asynchronous generator and an externally excited synchronous motor would preferably be used.

In order to prevent the electric motor being reversed prematurely when the main engine is rapidly reversed, the auxiliary circuit of the switches S₁ and S₂ is only closed by a centrifugal switch driven from the shaft of the piston steam engine, when the propeller shaft has approximately come to rest. In this way, even in the case of a rapid reversal, the electric motor will only be reversed when the speed of revolution has sunk very low. The effect of this is that the reversal of the electric motor can only take place when there is practically no load. The current impulse which takes place on the reversal of the motor can be minimized, for instance by the field of the motor being weakened through a relay being operated by a centrifugal switch driven from the generator shaft, which relay connects up a resistance in the exciter circuit. In operation, when the speed of the generator shaft drops substantially below normal speed, upon reversal of the engine K, the centrifugal switch closes, as shown, to effect opening of the relay switch which is spring-biased to closed position. The resistance shown is then effective to weaken the field of the motor M. When the generator shaft regains its normal speed, the relay switch is deenergized, as will be apparent, and the field resistance is therefore short-circuited.

The generator G will actually supply power to the motor M for forward rotation af-

ter the lever U has been moved to the left-hand, astern position. This action, however, does not appreciably interfere with the described control action because it persists for 5 only a very short time, that is, a few seconds which elapse while the engine K slows down to the point whereat the centrifugal switch associated with the shaft P is closed.

A similar controlling arrangement may be 10 effected in the case of ships having more than one shaft, an independent exhaust steam turbine set being preferably co-ordinated to each propeller shaft. In the propulsion of ships by means of Diesel engines 15 or other internal combustion piston engines, it is of course possible to use the exhaust gas turbine in place of an exhaust steam turbine.

Having now particularly described and 20 ascertained the nature of my said invention and in what manner the same is to be performed, I declare that what I claim is:—

1. In a ship propulsion system, a propeller shaft driven by a reversible engine and a reversible motor, a turbine driven by 25 exhaust fluid from the engine and in driving relation with a generator for supplying current to the motor, a reversing gear for the engine, switch means for controlling the supply of current from the generator to the 30 motor, an auxiliary circuit interconnecting said reversing gear and said switch means, and a centrifugal switch means in driving 35 relation with said shaft operative to permit establishment of said auxiliary circuit only when the shaft has approximately come to rest from either direction of rotation.

2. In a ship propulsion system, a propeller shaft driven by a reversible engine and a reversible motor, a turbine driven by 40 exhaust fluid from the engine and in driving relation with a generator for supplying current to the motor, a reversing gear for the engine, switch means controlling the supply of current from the generator to the motor, means interconnecting said reverse gear and 45 said switch means for changing the direction of rotation of said motor, and means comprising a centrifugal switch actuated responsive to and in dependence upon the 50 speed of rotation of the said generator operative to vary the field excitation of said motor at times of reversal of direction of rotation of the latter.

3. In a ship propulsion system comprising 55 a propeller shaft, a reversible engine in driving relation with said shaft, a reversing gear for said engine, a turbine driven by exhaust fluid from said engine, a generator driven by said turbine, a reversible motor in driving 60 relation with said shaft and disposed to be connected with said generator through said reversing switch means, means operable in dependence upon the speed of rotation of the said shaft effective to control actuations 65 of said switch means, and means associated

with and operable responsive to actuations of said reversing gear effective upon actuations thereof to control reversing actuations of said switch means in dependence upon the operative actuations of the said means operable in dependence upon the speed of rotation of the said shaft. 70

4. In a ship-propulsion system, an engine, a motor, a turbine, a connection supplying said turbine with the exhaust from 75 said engine, a propeller shaft, said engine and said motor being in direct driving relation with respect to said shaft, a generator driven by said turbine for supplying said motor, switch means for reversing the 80 operating connections between said generator and said motor, a control circuit for said switch means, a member for effecting reversal of said engine, a centrifugal switch driven by the propeller shaft and forming 85 part of said control circuit, and switch means forming part of said control circuit and controlled by said member. 90

5. In a ship-propulsion system, an engine, a motor, a turbine, a connection supplying 95 said turbine with the exhaust from said engine, a propeller shaft, said engine and said motor being in direct driving relation with respect to said shaft, a generator driven by said turbine for supplying 100 said motor, switch means for reversing the operating connections between said generator and said motor, electromagnets for effecting respectively operation of said switch means in opposite senses, an excitation circuit for said electromagnets, a centrifugal switch driven by the propeller shaft and forming part of said circuit, a member for effecting reversal of said engine, and switch means controlled by said member for connecting said electromagnet selectively in 105 said circuit.

6. In a ship-propulsion system, an engine, a motor, a turbine, a connection supplying 110 said turbine with the exhaust from said engine, a propeller shaft, said engine and said motor being in direct driving relation with respect to said shaft, a generator driven by said turbine for supplying said motor, switch means for effecting reversal of said 115 motor, a control circuit for said switch means, a member for effecting reversal of said engine, means responsive to speed conditions of said shaft above a predetermined rate and operable at such conditions to render said switch means non-effective for the motor-reversing action thereof, and switch means forming part of said control circuit and controlled by said member. 120

In testimony whereof I have hereunto 125 subscribed my name this 25 day of July A. D. 1928.

WALTER SCHOENI.
